UNITED STATES PATENT OFFICE.

ERASTUS E. WINKLEY, OF LYNN, MASSACHUSETTS.

FLYING-MACHINE.

1,200,288.

Specification of Letters Patent.

Patented Oct. 3, 1916.

Application filed October 31, 1908. Serial No. 460,435.

To all whom it may concern:

Be it known that I, ERASTUS E. WINKLEY, citizen of the United States, residing at Lynn, in the county of Essex and State of Massachusetts, have invented certain new and useful Improvements in Flying-Machines; and I do hereby declare the following to be a full, clear, and exact description of the invention, such as will enable others skilled in the art to which it appertains to make and use the same.

This invention relates to flying machines and more particularly to that class in which the weight is sustained by the reactions resulting when one or more supporting sails, or aeroplanes, are moved through the air edgewise at a predetermined angle of incidence, either by the application of mechanical power or by the utilization of the force 20 of gravity.

One feature of the invention contemplates a control of the vertical flight by an automatic preservation of the equilibrium thus effecting a maintenance of the machine at a 25 constant level when any desired height from the ground has been reached, or insuring a maintenance of the machine at the proper angle to the horizontal when ascending or descending. To preserve the equilibrium 30 means should be provided to maintain both the fore and aft and the lateral balance, that is, to provide for a restoration of the machine to its normal flying position, that is, its predetermined angular relation to the 35 horizontal, when such angular relation has been disturbed by a dipping in any direction. This object of the invention may be attained by the provision of means for automatically varying the degree of the angle 40 of incidence of the supporting sail, or aeroplane, proportionately to the amount of rectification, either longitudinally or laterally, that may be required to restore the lost equilibrium.

45 A further feature of the invention contemplates a control of the horizontal flight, or the direction of flight in a substantially horizontal plane, by means of a steering apparatus operating automatically to restore 50 the machine to any given course upon a deviation therefrom. It will be understood, however, that this feature of the invention is not confined in its application to flying machines but may be applied to ships, automobiles, torpedoes, or any other moving vehicle or object in the operation of which it is

desired to maintain at times a constant course in a predetermined direction. In its broader aspect this feature of the invention comprises a controlling mechanism for controlling or guiding the direction of movement of any moving object in a given path. In accordance with this feature of the invention means is provided, controlled by a deviation of the machine from the given course, to turn the aeroplane in a direction to restore the machine to its given course, the turning movement imparted being always proportionate to the degree of the deviation from the course.

In the preferred form of the invention a flat aeroplane, elongated transversely to the line of flight, is used, and the automatic means for restoring the lateral balance of the machine is controlled directly by any variation in the lateral balance of the aeroplane and operates to instantly increase the angle of incidence of the aeroplane at that side of the machine which has descended and to decrease the angle of incidence of the aeroplane at that side which has ascended. One mode of accomplishing this result is by imparting to the surface of the aeroplane a helicoidal warp about a substantially central transverse axis. The automatic means for restoring the fore and aft balance of the machine is controlled directly by any dipping of the aeroplane, either forward or backward, and operates instantly to increase the angle of incidence throughout the entire transverse length of the aeroplane for a forward dipping and to decrease said angle for a backward dipping. The automatic steering apparatus for governing the horizontal flight of the machine is connected to a vertical rudder and operates instantly to turn the rudder in a direction to restore the machine to its given course. This means is controlled directly by any angular movement of the machine about a substantially vertical axis.

In the construction of the machine illustrated in the drawings, there is employed a pair of parallelly arranged aeroplanes the equidistance of which is maintained by suitably arranged stanchions connected at their ends to said aeroplanes by hinged, or universal, joints. These aeroplanes are mounted in a rigid supporting frame from which the frame sustaining the motor and automatic rectifying mechanism depends. The motor frame is provided with front and

2
 rear trunnions on which the aeroplane frame is loosely journaled thereby permitting free movement of said aeroplanes in a vertical plane about said trunnions as a fulcrum. The aeroplane supporting frame is U-shaped and the aeroplanes are journaled in its arms on transversely arranged pivots, thus permitting a free variation in the angle of incidence. The motor frame sustains a 5
 10 slidingly mounted, constantly rotating centering, or lateral-balance-restoring, cam or equivalent device, which controls actuating mechanism for operating the devices for warping the surfaces of the aeroplanes to vary the angle of incidence in the manner 15 described. The position of this cam relative to the aeroplane warping actuating mechanism, is directly affected by a change in the lateral balance of the aeroplanes and the 20 position of the cam, thus defined, determines the degree to which the angle of incidence at each side of the center of the machine is to be varied by the aeroplane warping operation. In a similar manner a fore and aft 25 dipping of the machine affects the position of a similarly mounted cam or device for determining the action of suitable actuating mechanism for operating the devices for varying the degree of the angle of incidence 30 of the aeroplanes in the same direction on both sides of the center of the machine.

The automatic steering apparatus also is provided with a movably mounted centering cam, or equivalent device, operating 35 upon the rudder stock, or a connection thereto, to turn the rudder. The position of this cam and, therefore, the angular position of the rudder, is determined by means of a 40 feeler adapted to contact with a gage device mounted to swing with the compass needle. The gage is movable relatively to the compass needle and its angular position relative thereto determines the course to be held.

45 To the accomplishment of the above named objects and such others as may hereinafter appear, as will be readily understood by those skilled in the art, the invention comprises the features and combinations 50 of mechanisms hereinafter described and particularly pointed out in the appended claims.

The preferred embodiment of the invention is illustrated in the accompanying drawings in which—

Figure 1 is a front elevation of the machine with parts broken away to show details of construction; Fig. 2 is an elevation of the right hand side of the machine; Fig. 3 is an enlarged detail in vertical longitudinal section of the mechanisms for restoring the equilibrium of the machine; Fig. 4 is an enlarged detail in front elevation of the mechanisms shown in Fig. 3 with the 65 front of the float tank removed; Fig. 5 is an

enlarged detail in vertical transverse section viewed from the rear on the line 5—5 of Fig. 3; Fig. 6 is a plan of the mechanisms shown in Fig. 5 with the operating devices above the gearing removed; Fig. 7 is a detail, in plan, of the end connection of the aeroplane to its supporting frame; Fig. 8 is a plan of the automatic steering apparatus showing the machine set on a course due east; Fig. 9 is a plan of the parts shown in Fig. 8 illustrating a deviation of the machine from its course due east to a course east northeast, the parts being shown in the relative positions assumed just before the rudder is turned; Fig. 10 is a detail of a portion of the mechanism shown in Fig. 9 illustrating the relative positions of the parts after the rudder has been turned; Fig. 11 is a rear end elevation, of the steering apparatus; and Figs. 12, 13 and 14 are transverse sections, in elevation, on the lines 12—12, 13—13 and 14—14 of Fig. 8.

In the embodiment of the invention illustrated in the drawings, the flying machine has been shown as comprising two parallel superposed aeroplanes and this construction is preferred, although the invention may be embodied in a structure having a single aeroplane. The machine is provided with an aeroplane supporting frame comprising a rectangular structure or framework 2 the lateral ends of which support transversely extending spars 4, two on each side, which converge at their outer ends as at 6 (Fig. 7). At the converging ends 6 there are provided uprights 8 and 8^a so that the aeroplane supporting frame is of substantially U-shape. The parts thus far described are all rigid one with the other. The rectangular framework 2 is provided with a pair of bearings 10 in which is journaled a rock shaft extending transversely of the machine and horizontally above the spars 4. This rock shaft is formed in two parts 12 and 12^a, the break between them occurring substantially centrally of the machine. The part 12 of the rock shaft is provided at its outer end with a trunnion 14 adapted to enter a horizontal bearing in the upright 8. The rock shaft 12^a is similarly provided with a trunnion 14^a adapted to enter a horizontal bearing in the upright 8^a (see Fig. 7). The trunnion 14^a forms one arm of a cross coupling, the opposite arm of which is secured to the rock shaft 12^a and the transverse arms of which are secured to fore and aft spars 16^a forming a portion of the frame of the lower aeroplane. The spars 16^a at their outer ends are provided with sockets in which rest balls on the ends of transversely arranged spars 20, thus forming ball and socket joints 18^a between the spars 16^a and 20. The spars 20 are connected by similar ball and socket joints 18 to the ends of fore and aft spars 16 connected to the outer end 130

of the rock shaft 12 by means of a cross coupling (see Fig. 1). To the outer ends of the spars 16^a are attached by hinged joints the lower ends of upright stanchions 22^a (see Fig. 2.), the upper ends of which stanchions are connected by similar hinged joints to a fore and aft spar 24^a superposed above the spars 16^a. The spar 24^a is provided with a centrally arranged trunnion 26^a which 10 enters a horizontal bearing in the upper end of the upright 8^a. The spar 24^a is provided with sockets at its ends which receive balls on the ends of transverse spars 28 which are superposed above the transverse spars 15 20. The spars 28 are connected by ball and socket joints at their other ends to the outer ends of a fore and aft spar 24 superposed above the spars 16 and journaled in the upper end of the upright 8 in a similar manner to the journaling of the spar 24^a. The 25 spar 24 is connected at its ends to the ends of the spar 16 by means of stanchions 22 hinged at each end. With this construction the spars 16, 16^a and 20 form the frame of one aeroplane and the spars 24, 24^a and 28 30 form the frame of a second aeroplane superposed above the first and parallelly arranged therewith. Cloth or other suitable fabric is spread over the frames so formed, thus producing sails offering a proper resistance to the air currents. The horizontal bearings of the trunnions 14 and 14^a, 26 and 26^a in the uprights of the aeroplane supporting frame 35 permit the aeroplanes to have an angular movement about horizontal transverse axes so that the angle of incidence at which they are presented to the atmosphere may be varied. The flexible joints between the ends of the stanchions 22 and 22^a and the fore 40 and aft spars permit this angular movement to take place while maintaining the equidistance on the aeroplanes from each other.

The rectangular framework 2 is provided with front and rear bearings 30 in which 45 are journaled trunnions 32 formed at the front and rear of the upper part of a motor, and equilibrium restoring mechanism supporting frame 34. The frame 34 is constructed of conveniently formed castings 50 suitably connected for supporting the various parts forming the mechanisms referred to. The motor cylinders are indicated generally by M (Figs. 1 and 2), and are supported by means of depending brackets 36. The motor 55 imparts a rotary motion to the main driving shaft 38, at the forward end of which there is mounted the usual balance wheel W and any suitable and convenient form of propeller P. The motor may be of any 60 suitable and convenient construction and, therefore, need not be described in detail. A horizontal counter-shaft 40 journaled in brackets 41 on the motor frame is driven from the main shaft 38 by the means of a 65 sprocket wheel and chain connection 42.

The counter-shaft 40 has pinned thereto a bevel gear 44 which meshes with a second bevel gear 46 on a vertically arranged counter-shaft 48 suitably journaled in bearings 49 (see Fig. 5) in the motor frame. The 70 counter-shaft 48 is the actuating shaft for the automatic mechanism for restoring the lateral balance of the machine when said balance is disturbed and this mechanism will now be described.

Mounted on the counter-shaft 48, so as to permit a sliding movement along said shaft, is a centering cam 50. This cam is in the form of a cylinder or sleeve having on its outer surface a pair of cam projections extending for but a short angular distance around the sleeve. These projections also extend from the ends of the sleeve inwardly along its surface but terminate in positions to leave them far enough apart to permit the passage of a cam roll. They are also formed with a flaring, or V-shaped, approach. These cam projections are of substantially triangular form as shown best by dotted lines at 52 in Fig. 5. A perspective of the cam 50 is shown in Fig. 2 and this view well illustrates the flaring opening between the projections 52. The sleeve on which the cam projections 52 are formed is provided with a peripheral groove 54 at one end, into which there projects a roll 56 on one end of a lever 58 fulcrumed in the motor frame 34 and connected at its other end, by means of a link 60, to a lug on one end of the rectangular framework 2. 100 From the lever 58 there projects an arm 62 provided with a segment 64. This segment is adapted to be borne upon by a pair of rolls 66 carried in a suitable bearing on the motor frame 34 and arranged with their peripheral surfaces in contact with the surface of the segment 64 (see Fig. 5). These rolls are spring pressed inwardly and, when in their inward position, act as a lock to prevent movement of the segment. The 105 rolls may be forced outwardly against their springs to unlock the segment by an inward movement of a wedge pin 68 mounted for movement between them. The wedge pin 68 is actuated to unlock the segment 64 110 by means of a lever 70 fulcrumed in the motor frame 34. One end of the lever bears on the head of the pin 68 and the other end of the lever carries a roll 72 arranged to be engaged by a cam 74 mounted on the counter-shaft 48 and constructed to rock said lever about its fulcrum.

The counter-shaft 48 is provided with a second cam 76 similar to cam 74 which engages a roll 78 on one end of a lever 80 fulcrumed in the motor frame 34, the other end of which lever bears upon the head of a wedge pin 82 operating a similar locking device to that just described and adapted to engage a segment 84 carried by a lever 125 130

86 fulcrumed in the motor frame 34. The lever 86 is provided at its free end with a cam roll 87 arranged to be engaged by the cam projections 52 of the centering cam 50. 5 The lever 86 is connected, by means of a link 88 (Figs. 3 and 5), to the outer end of a horizontal crank arm 90 (Fig. 6), the inner end of which is connected to a sleeve 92^a loose on the part 12^a of the aeroplane rock 10 shaft and held on the end of said shaft by means of a collar 93^a. The sleeve 92^a is formed on the end of a vertical arm 94^a provided at its upper end with a gear segment 96^a which meshes with an idle gear 15 98 pivoted in a cross bar 99 (Figs. 3 and 5) extending over the upper part of a box like structure 100 carried by the rectangular framework 2. Diametrically opposite the gear segment 96^a is a second gear segment 20 96, also meshing with the idle gear 98, which segment is mounted on the end of a vertical second arm 94 provided with a sleeve 92 loose on the inner end of the part 12 of the aeroplane rock shaft and held in 25 place by a collar 93. The arms 94 and 94^a are respectively provided on their outer surfaces with vertical guide-ways 102 and 102^a in which are arranged slides 104 and 104^a. The slides 104 and 104^a are provided with 30 slots 106 and 106^a, which slots are diagonally arranged for a purpose to be hereinafter described. The rock shafts 12 and 12^a are provided respectively with vertical crank arms 108 and 108^a, rigidly connected 35 to said shafts, and having at their free ends horizontal crank pins 110 and 110^a which enter the slots 106 and 106^a respectively. With the construction just described, it will be seen that the aeroplane supporting 40 frame is fulcrumed for angular movement in a substantially vertical plane about a horizontal fore and aft axis, namely, the trunnions 32. If the machine meets with any force or excess pressure which tends 45 to disturb the lateral balance of the aeroplane, the aeroplane supporting frame will be caused to rotate about this axis. A descent of the right hand end of the aeroplane, viewing Fig. 1, will move the link 60 50 connecting the aeroplane supporting frame with the lateral balance restoring mechanism downward, while a descent of the left hand end of the aeroplane will cause said link to move upward.

55 Assuming, for purposes of illustration, that the right hand end of the aeroplane has moved downward, the downward motion of the link 60 will be communicated to the lever 58 and, when the cam 74 has been rotated 60 to a position to release the locking device for the segment 64, the lever 58 will act to move the sleeve, on which the centering cam 50 is formed upward. This movement occurs at the time, during the rotation of the centering cam, when the roll 87 is removed

from its position, as shown in Fig. 5, between the cam projections 52. The locking device for the segment 64 is but momentarily released and immediately relocks the lever 58 after its movement, thus holding 70 the cam 50 in its new position. The cam 76 now operates to release the locking device engaging the segment 64 and as the cam 50 rotates the slanting portion on the approach side of the lower cam projection 52 will engage the roll 87 and will cause a movement of the lever 86 upward about its pivot, thereby forcing the link 88 also upward, whereby an upward pressure is exerted on the outer end of the crank 90. The segment is again 80 locked in its new position as soon as the roll 87 has been centered in the cam 50. This movement acts to rotate the gear segment 96^a rearwardly and the engagement of the slotted slide 104^a with the pin of the crank 85 108^a acts to rock the part 12^a of the aeroplane rock shaft rearwardly in a counter clockwise direction when viewing the shaft from the left hand side of the machine. A movement of the segment 96^a communicates 90 a movement, in the opposite direction, however, to the segment 96 through the intervention of the idle gear 98. The segment 96 is moved toward the front of the machine 95 whereby the part 12 of the rock shaft, through the connection of the crank 108 to the slotted slide 104, is rotated in a clockwise direction when viewed from the left hand side of the machine. These opposite rotations of the two parts of the rock shaft 100 operate to turn the end spars 16 and 24 of the aeroplanes in a clockwise direction about their trunnions 14 and 26 as pivots when viewed from the left hand side of the machine, and to turn the end spars 16^a and 24^a 105 in a counter clockwise direction about their trunnions 14^a and 26^a as pivots when viewed from the same side of the machine. These movements of the end spars impart to the 110 surfaces of the aeroplanes a helicoidal warp about a central transverse axis which, in this instance, is the rock shaft itself for the lower aeroplane. The surfaces of the aeroplanes are warped in such a manner that their opposite lateral side portions are moved to different positions relative to the normal plane of the bodies of the aeroplanes, the angle of incidence on that side of the aeroplanes which has descended being increased and the angle of incidence on that side of the 115 aeroplanes which has ascended being decreased.

It should be understood, however, that the invention is not limited to the particular manner described in which the aeroplanes 120 are manipulated to vary the angular relation of their opposite end portions in opposite directions with respect to their normal planes, as any automatically operating mechanical means or construction whereby this 125 130

result is obtained comes within the spirit and scope of the invention.

An increase in the angle of incidence of the aeroplanes on that side which has descended owing to a disturbance of the lateral balance permits a greater leverage by the air currents on that side, which greater leverage acts to restore the lateral balance. Any lifting movement imparted, however, will also lift the link 60 which will act to rotate the lever 58 about its pivot in a direction to move the centering cam 50 again downward toward its normal position. The locking and unlocking action on the segments 64 and 84 again occurs on the next rotation of the counter-shaft 48 and during this rotation the roll 87 on the lever 86 will be engaged by a portion of the slanting portion on the approach side of the upper cam projection 52 but somewhat nearer the center of the cam, owing to the lesser return movement, than the portion of the lower cam projection which engaged said roll on the previous rotation of the cam. The downward movement of the link 88 will, therefore, be less than the upward movement imparted to it on the previous rotation of the cam and the aeroplane rock shaft parts 12 and 12^a will be rotated through a smaller angular movement, thereby diminishing the degree of the warp imparted to the aeroplanes. This process of diminishing the degree of the warp by small increments will continue until the lateral balance of the aeroplanes has been restored, at which time the centering cam 50 will have been moved to its normal or central position as shown in Fig. 5, in which position the lever 86 is unaffected by its rotation.

If the left hand side of the aeroplanes should descend the link 60 will be drawn upward and the centering cam 50 will be moved downward along the cam shaft 48 instead of upward, which will cause the upper cam projection 52 to first engage the roll 87 thereby pulling the link 88 and the crank downward and thus rotating the parts 12 and 12^a of the aeroplane rock shaft in the opposite directions to those described for a descent of the right hand side of the aeroplanes. This will warp the aeroplanes in an opposite direction but about the same axes and will, therefore, increase the angle of incidence on the left hand side of the aeroplanes and decrease the angle of incidence on the right hand side. A restoration of the lateral balance will then automatically take place, by increments on each revolution of the countershaft 48, in the same manner as just described for restoration of the lateral balance after a descent of the right hand side of the aeroplanes.

Thus far there has been described merely the automatic mechanism for restoring equilibrium of the machine when its lateral bal-

ance has been disturbed by excess vertical pressure on either end portion of the aeroplanes, but the equilibrium of the machine may also be overcome by an excess vertical pressure on either the front or rear portions of the aeroplanes. Such excess pressure will cause the machine to dip either backward or forward, thus causing an undesired ascent or descent of the machine. Means to automatically maintain the fore and aft balance of the machine will now be described.

The motor frame 34 sustains a tank 120 for containing oil or any other suitable liquid the surface of which is not too readily disturbed. Extending transversely across this tank is a stud 122 on which is loosely mounted a sleeve or hub of a support 124 for a pair of floats 126, one on each side of the stud 122. Also loosely mounted on the stud 122 is the hub of a lever 128. The floats are connected to the lever 128 in a manner so that they may be placed in any angular relation thereto by means to be described hereinafter. The lever 128 is provided at its free end with a roll 129 which enters a peripheral groove in one end of a sleeve on which is formed a centering cam 130 similar in all respects to the centering cam 50 heretofore described in connection with the lateral balance restoring mechanism. The cam 130 is slidably mounted upon a horizontally arranged countershaft 132 suitably journaled in the motor frame and driven from the counter-shaft 40 by means of a sprocket and chain connection 100 134 (see Fig. 2). The lever 128 is also provided with a segment 136 (Fig. 3) borne upon by a locking device 138 similar to those heretofore described and operated by means of a lever 140 fulcrumed in the side 105 of the tank 120 and actuated by means of a cam 142 on the counter-shaft 132. The counter-shaft 132 is provided with a second cam 144 which is borne upon by a cam roll on one end of a lever 146 fulcrumed in 110 a bearing projecting from the side of the tank and having at its other end a roll engaging between collars of a sleeve 148 adapted to slide on a stud shaft 32^a which may conveniently be formed as a continuation of 115 the forward trunnion 32 of the motor frame and which is sustained in suitable bearings 29 and 31 carried by said frame and box 100 respectively. The sleeve 148 is also engaged by a roll on one end of a lever 150 (Fig. 3) 120 fulcrumed in a projection from the box-like structure 100, the other end of which lever operates a locking device 152, similar to those heretofore described. This locking device 125 co-operates with a segment 154 forming a part of a lever 156 fulcrumed on a cross pivot in the box 100. The lower end of the lever 156 is provided with a roll 158 which engages between the collars of a sleeve 160 free to slide on the stud shaft 32^a. 130

This sleeve is also engaged by a roll on the upper side of the free end of a horizontally arranged lever 162 (Fig. 4) fulcrumed on a vertical pivot pin 163 in a suitable support 164 rising from the side of the tank 120. The lever 162 is also provided with a cam roll 165 at the lower side of its free end, which is adapted to be engaged by the cam projections 131 of the centering cam 130. A horizontal link 166 connects the upper end of the lever 156 with the vertical arm of a bell crank 168 fulcrumed for movement about a horizontal pivot pin 170 in a bearing 171 rising from the box 100. The hub 15 of this bell crank is connected by a tie piece 172 to a second hub from which there projects rearwardly a horizontal arm 174 parallelly arranged with the horizontal arm of the bell crank. These horizontal arms are connected, by links 176 and 176^a, to the slides 104 and 104^a having obliquely arranged slots 106 and 106^a. The purpose of the oblique arrangement of these slots will now be clear. With the construction just described if there is excess vertical pressure, say on the under sides of the front portions of the aeroplanes, the motor frame 34 which carries the tank 120 is tipped forwardly and upwardly but, of course, the level of the oil within the tank remains unchanged and the floats 126 must necessarily retain their original relation to the surfaces of the oil, that is, a line drawn through their center remains horizontal. This retention of the floats in a horizontal position acts to move the lever 128 to the left in Fig. 3 and with it the centering cam 130, the cam 142 having at this time released the segment 136 so that a movement of the lever 128 may occur, but again immediately relocking the segment to retain the centering cam in its new position on the counter-shaft 132. The lock 152 for the segment 154 of the lever 156 is then released by the action of the cam 144 and the lower end of the lever 156 is moved to the left in Fig. 3 by the action on the right hand cam projection 131 on the centering cam roll 165 of the horizontal cam lever 162. This movement of the lever 156 operates to turn the bell crank 168 in a direction to raise the links 176 and 176^a whereby the slides 104 and 104^a are raised. This causes the diagonal slots 106 and 106^a to act in a manner to throw the cranks 108 and 108^a forward, thereby rotating the parts 12 and 12^a of the rock shaft simultaneously and both in a clockwise direction when viewing said shaft from the left hand side of the machine. This movement of the rock shaft turns the end spars of the aeroplanes all in the same direction about their horizontal pivots and decreases the angle of incidence presented by the aeroplanes to the atmosphere to an equal degree throughout the entire width of the aeroplanes. This decrease in the angle of incidence acts to restore the fore and aft balance to some degree. A partial restoration of the fore and aft balance of the machine will alter the angular relation of the machine to the surface of the oil in the tank, which in turn will cause a corresponding return of the lever 128 toward its normal position which will carry the cam 130 back toward its central or normal position. The action of restoring the fore and aft balance by increments will continue in a similar manner to that described for restoring the lateral balance until the fore and aft balance is fully restored at which time the centering cam 130 will have reached its normal or central position in which position the lever 156 is unaffected by its rotation. A similar action will occur if an excess vertical pressure is placed upon the under sides of the rear portions of the aeroplanes so that the motor frame 34 is tipped backwardly and upwardly, the only difference being that the centering cam 130 will in that case initially be moved to the right in Fig. 3 instead of to the left. The means heretofore described for maintaining the equilibrium of the machine are utilized after a desired height or level has been attained or during the ascent or descent of the machine while in the air. In other words, if the machine is sailing in any particular plane, horizontal or otherwise, the automatic equilibrium restoring means described will maintain the machine in substantially that plane. Means should be provided, however, for varying the angle of the plane in which the machine is sailing and, preferably, such means should be under control of the operator. The angle to the horizontal at which the machine sails is, of course, controlled by the degree of the angle of incidence presented to the atmosphere by the aeroplane. The purpose of the adjustable connection between the floats 126 and the lever 128 (Fig. 3) heretofore referred to is to vary the degree of the angle of incidence of the aeroplanes when it is desired to vary the angular direction of the course in a vertical plane. The hub of the support 124 for the floats is provided with a conveniently located segment 177 (Fig. 3) which has movement beneath an overlapping bracket 178 carried by the lever 128. This bracket is provided with a spring pressed pin 179 passed transversely therethrough and adapted to enter one of a series of holes made for its reception in the segment. The pin 179 may be provided with a handle at its outer end which is seized by the operator when changing the pin from one hole to another in the segment. This construction permits the operator to shift the centering cam 130 on its shaft, independently of the action of the

floats, and thereby change at will the degree of the angle of incidence presented by the aeroplane to the atmosphere. When the new plane has been attained the floats and lever are again locked together and the equilibrium is automatically taken care of, in the new plane, by the means and in the manner heretofore described.

In flying through space, as when sailing 10 on the ocean, where no set path must be followed in going from point to point, an air line will preferably be followed and, therefore, the machine will usually be kept on the same course for some length of time before said course is changed. It will be obvious to those skilled in the art that in the different strata of the air there will be varying wind pressures encountered which will cause the machine to veer from the course 15 which has been laid, to one side or the other according to the nature of the currents. In order to simplify the handling of the machine, and to decrease the strain on the operator by decreasing the number of subjects 20 to which his attention must be constantly directed, it is desirable that the machine be provided with an automatic steering apparatus for maintaining the ship on any predetermined, or given, course after said course 25 has once been laid.

It will also be obvious to those skilled in the art that when the lateral balance of the machine has been disturbed and is being restored by means of the automatic mechanism heretofore described, in the operation 30 of which the angles of incidence at the opposite lateral end portions of the aeroplane are altered, the side of the machine on which the angle of incidence has been decreased 35 will offer less resistance to the atmosphere than that side on which the angle of incidence has been increased. There will, therefore, be a tendency, during the operation of restoring the lateral balance of the machine, 40 for it to swing about a substantially vertical axis, the side having the smaller angle of incidence moving forward. It is important that this tendency to rotate about a vertical axis be overcome as, of course, such rotation 45 will change the course to which the machine has been laid. An automatic steering apparatus is, therefore, of particular advantage in a machine of the type herein described as it can be utilized to present automatically 50 to the wind, on that side of the machine having a smaller angle of incidence, an increased resistance by means of a suitable guiding device, such as a rudder. This will effectually overcome the tendency of the 55 machine to turn and will maintain the predetermined course during the operation of restoring the lateral balance.

Referring now to Fig. 2 it will be seen 60 that the countershaft 40 is extended rearwardly in a fore and aft direction and

passed beneath the bowl 180 of a mariner's compass which is supported by gimbals upon a platform 182 at the rear of the automatic equilibrium restoring mechanisms heretofore described. The outer and inner gimbal 70 rings are respectively designated by 207 and 208 (Fig. 12). The outer gimbal ring is provided with trunnions 215 and 217 supported in suitable fore and aft bearings 222 and 223 (Fig. 8) rising from the platform 75 182. The inner gimbal ring is provided with trunnions 211 and 213 (Fig. 12) which are supported in suitable transverse bearings 219 and 221 in the gimbal ring 207. The platform 182 is provided with a rudder 80 frame 184 in which is mounted a vertical rock shaft 186 forming a rudder post to which a balance-rudder 188 is secured. The rock shaft 186 is provided near its base with a crank 190 (Fig. 2) which is operatively 85 connected to the automatic steering apparatus now to be described.

The compass bowl 180 is provided centrally (see Fig. 12) with a vertically arranged pointed pin 194 on the upper end of 90 which loosely rests the magnetic needle 196, said needle being provided with a cone shaped socket 197 in its under side to fit over the top of the pin 194 and maintain it in place. The needle is also provided with 95 a central boss on its upper side above the socket 197. This boss is provided with a projecting screw 198. The usual compass card 200 is mounted on the needle boss, and the needle and card are secured to each other 100 so as to move together in the usual manner. On top of the compass card and rotatably mounted on the needle boss is a gage device 202 which may be held in any desired angular relation to the compass card and 105 needle by means of a thumb nut 204 threaded on the screw 198. The gage device 202 is provided with a pointer 206 (Fig. 8) by means of which the direction of the course 110 to be maintained is determined. This pointer may be turned to any desired point on the compass that has been chosen as the course upon which the machine is to sail, by loosening the thumb nut 204 and then turning the gage device by hand to position. 115 The initial determination of the course is then under control of the operator.

The trunnion 213 of the gimbal 208 from which the compass bowl 180 is supported is provided with a slide-way for the reception of a sliding pin, or feeler, 210 adapted 120 to contact with the surface of a gage device 202, which surface is formed as the arc of a circle the center of which is eccentric to the center of the compass. Fulcrumed 125 in a suitable bracket 212 extending from the gimbal 207 is a horizontally arranged bell crank 214, one arm of which is forked and is provided with rolls engaging a collared sleeve 216 rigidly secured to the outer end 130.

of the feeler. The other arm of the bell crank is also forked (Fig. 13) and provided with rolls engaging between two collars on a slidably mounted sleeve 218 on a 5 counter-shaft 220 which is a continuation of the trunnion 217. The bell crank is thus wholly sustained by the compass. The feeler 210 is maintained in contact with the gage device 202 by means of a suitably connected spring 209.

10 The sleeve 218 is provided with a second pair of collars which engage a roll on the upper side of a horizontal lever 224 (Fig. 14) provided with a long hub 225 fulcrumed 15 on a vertical pivot pin supported by means of a lower bearing on the floor of the platform 182 and an upper bearing in a bracket 226 rising from said platform. The horizontal lever 224 is provided with a roll at 20 its under side adapted to be engaged by the surface of a cam 228 mounted on the counter-shaft 40. This cam (see Figs. 8 and 14) is provided with a comparatively short rise, 25 a long idle portion at the top of the rise and a sharp drop to the bottom of the rise so that the actuating portion of the cam occupies a comparatively short angular space. The lower end of the hub 225 is provided 30 with a crank 230 forming, in effect, an extension of the lever 224 but on a lower plane. The crank 230 is provided with a segment 232 (Fig. 8) which is borne upon by a friction roll locking device 234; similar to those heretofore described, operated 35 by a lever 236 fulcrumed on the platform 182 (see Fig. 13) and controlled by means of a cam 238 mounted on the counter-shaft 40. The free end of the crank 230 is connected by means of a longitudinal link 240 40 to one end of a transverse lever 242 (see Fig. 8) fulcrumed on the platform 182. The other end of the lever 242 carries a roll which enters between collars on a sleeve 45 slidably mounted on the counter-shaft 40 on which sleeve there is formed a centering cam 244, by means of cam projections 246, all as heretofore described for the centering cams 50 and 130 used in connection with the equilibrium restoring mechanisms. 50 The centering cam 244 engages a roll on one end of a lever 248 which lever is provided with a segment 250 borne upon by a friction roll locking device 252 similar to those heretofore described, operated by a lever 254 (Fig. 55 13) fulcrumed on the platform 182 and controlled by means of a cam 256 on the counter-shaft 40. A suitable operative connection, shown as a link 260 (Figs. 2 and 10), extends from the free end of the centering 60 cam lever 248 to the end of the crank 190 which is secured to the rudder post 186.

At the rear end of the counter-shaft 40 there is mounted a cam 262 (Figs. 8 and 14) which engages a roll on the lower side of a 65 horizontally arranged lever 264 fulcrumed

on a vertical pin in a post 266 rising from the platform 182. The upper side of this lever is provided with a roll which enters between the collars of a sleeve 272 loosely mounted on a stud shaft 274 which is 70 formed as a continuation of the trunnion 215. This sleeve is also engaged by a roll on the end of the transverse arm of a horizontally arranged bell crank lever 268 fulcrumed on a suitable bracket 270 extending 75 from the gimbal ring 207. The longitudinal arm of the bell crank 268 is provided with a forked end having rolls engaging between the collars of a sleeve 276 rigidly connected to a wedge pin 278 (Fig. 12) slidably 80 mounted in a horizontal guide-way in the trunnion 211 of the gimbal 208. The wedge pin 278 is adapted to enter between the shanks of a pair of vertically movable jaws 280 pivoted (Fig. 8) on a pin 282 in a recess 85 formed at the inner side of the gimbal 208. The jaws 280 extend inwardly a sufficient distance to enable them to seize the margin of the compass card 200. The jaws are normally maintained open by means of suitably mounted leaf springs 284. The wedge pin 278 is normally maintained withdrawn from its engagement with the shanks of the jaws 280 by means of a coil spring 286 (Fig. 8) extending between a collar 288 on 90 the end of the stud shaft 274 and the collar 272 which is engaged by the transverse arm of the bell crank.

In explaining the operation of this automatic steering apparatus it will be assumed 100 that the chosen course to be maintained is due east. The pointer 206 is, therefore, placed in the position shown in Fig. 8, that is, with its pointed end superposed on the point marked "east" on the compass card. 105 While the machine is held to this course the center of the gage 202 will be opposite the feeler 210. The roll on the lower side of the horizontal lever 224, which is in engagement with the cam 228, is at this time 110 centrally of the rise on said cam as shown in Fig. 8. A rotation of the cam 228 will cause the sleeve 218 to be continuously reciprocated along the stud shaft 220 and the movement of this sleeve will communicate 115 a constant oscillation to the bell crank 214 which, in turn, acts to constantly reciprocate the feeler 210 into and out of engagement with the gage device 202. The actuation of the lever 224 by the cam 228 causes the centering cam 244 to slide on the shaft 40. This movement of the cam 244 is not communicated to the lever 248, however, because at this time, owing to the rotation 120 of the shaft 40, the cam surfaces 246 do not engage the roll carried by the lever 248. The rudder is therefore not turned and the course held by the machine not affected. The cam 262 is so timed that the wedge pin 278 is forced inwardly to cause the jaws 125

280 to clamp the compass card and hold it securely against any movement during the time that the feeler 210 is in engagement with the gage device. This is for the 5 reason that owing to the delicacy of the mounting of the compass needle a jar upon the gage device, which is rigidly connected therewith, would cause a derangement of the needle and affect disastrously the 10 proper operation of the compass. The feeler is held against the gage device during the time that the roll which is engaged by the cam 228 is located in the open space in said cam, and it is during the whole 15 of this time that the clamps 280 are closed. At all other times the clamps are open and the machine is free to rotate about a vertical axis without carrying the compass card with it.

20 If the condition of the wind pressure changes, or other disturbing forces are encountered which tend to throw the machine off its course, for instance, if it is headed in the direction east north east, as shown 25 in Fig. 9, instead of due east, as shown in Fig. 8, the whole machine will be swung around the compass card in a horizontal plane. In this particular case this will move the feeler 210 in a direction so that 30 when the cam roll engaging the cam 228 again drops off of the upper, or idle, portion of the cam, it will fall to a point nearer to the base of the cam than is shown in Fig. 8, owing to the greater inward movement 35 of the feeler before it comes in contact with the surface of the gage device 202. This greater inward movement of the cam roll throws the lever 224 forward and consequently throws the crank 230 aft, to the 40 position shown in Fig. 9. The locking device 234 has been unlocked by its operating means in time to permit this movement of the lever and crank to occur. The link 240 is moved aft which moves the lever 242 in 45 a direction to slide the centering cam 244 forward along the counter-shaft 40 to the position shown in Fig. 9. This occurs while the roll of the lever 248 for engaging said centering cam is in the open portion of the 50 cam. As the centering cam rotates the cam projection 246, at the left in Fig. 9, will engage the roll on the lever 248 and will force the cam end of said lever forward, the locking device 252 having been unlocked by its operating means in time to 55 permit this operation to occur. This movement of the lever 228 carries its free end in a direction to move the connecting link 260 to the rudder in a manner to turn the 60 rudder in a direction to cause the machine to be turned back toward its original course, that is, due east. Before the completion of the next rotation of the centering cam, the machine will have responded 65 to the action of its rudder so that the feeler

will engage a portion of the surface of the gage device somewhat nearer the center of said device than is shown in Fig. 9 and the centering cam will, therefore, through the connections described, have been moved aft 70 again, slightly, along the counter-shaft 40. The cam roll on the lever 248 will, therefore, on the next revolution of the centering cam be engaged by the cam projection 246 at the right of said cam, in Fig. 9, and the rudder connections will, therefore, be moved in a direction to bring the rudder back again toward its central or normal position. This operation will continue and the rudder will be brought back by small 75 increments at each revolution of the centering cam until it again reaches its central position at which time the feeler will again be engaging the center of the gage device, as shown in Fig. 8, which is the inactive 80 position. It will be understood, of course, that the locking devices 234 and 252 are operated in a similar manner to those heretofore described for the mechanisms for restoring the equilibrium, that is, after the 85 centering cam 244 has been moved to a new position it is held in such position until the rudder has been moved to its new position, and after the rudder has been moved to a new position it is held in that position 90 until the centering cam has again been shifted so as to bring the rudder to still another new position.

If it is now desired that the machine should fly in a course due west, the pointer 100 206 will be superposed above the point of the compass card designating the direction west. The gage device 202 will then be in a position diametrically opposite to that shown in Fig. 8. Under these conditions, 105 the feeler 210, not engaging the gage device 202, will, under the influence of the spring 209, be at the limit of its inward movement. Accordingly, the mechanism interposed between the bell crank lever 214 and the centering cam 244 will cause the cam 244 to 110 be moved along the shaft 40 so that the left-hand cam surface 246 will engage the cam roll on the lever 248 and thereby operate the link 260 to move in a direction to 115 swing the rudder to cause the machine to veer around 180° until the middle portion of the gage 202 is again in engagement with the feeler 210. At this time, the course of the machine will be due west. It will be 120 readily understood, then, that when the gage device 202 and the feeler 210 are not in engagement, the machine will be caused to veer around always in the same direction, by the mechanisms controlling the 125 rudder until the feeler is again brought into engagement with the middle or neutral portion of the gage device 202. When the feeler is in its neutral position, as heretofore described,—the rudder being in 130

longitudinal alignment with the line of flight,—the machine will hold to the course designated by the pointer 206.

From the foregoing description it will be apparent that under ordinary conditions of flight whatever the amount of deviation of the flying machine from its given course, the amount of rectifying movement imparted to the rudder to restore the flying machine to its course will be directly proportionate to the amount of deviation of the machine.

It will be observed that the mechanisms described provide an extremely efficient automatic control of the flight when any desired level is reached, or during an ascent or descent, while at the same time means is provided, under the control of the operator, for bringing the machine from one level to another, which is important as the machine should be under control of a human agency rather than a mechanical agency at such times and particularly when a flight is commenced or terminated.

It will be obvious to those skilled in the art that, if desired, the machine can with great ease be steered by hand so as to proceed on a circular course, or to dart back and forth in any desired, or required, direction, by means of a proper manipulation of the pointer 206 carried by the gage device 202. This is of great importance when sailing near the ground where obstructions may be encountered.

In the following claims all references to position or direction of movement of the elements are to be interpreted as terms of designation and not of limitation as obviously it is the relative position or relative direction of movement which is alone of importance. It will also be understood that the invention is not limited to the specific construction and arrangement of the parts shown and described, except in so far as such construction and arrangement is referred to in the claims.

Having explained the nature and object of the invention and specifically described the best form of the machine now known to me, what I claim as new, is:—

1. A flying machine having, in combination, a horizontally disposed sail arranged to move through the air edgewise and sustain its weight by the reactions resulting from such movement, propelling means, and automatically operating mechanical means controlled by the propelling means for restoring the equilibrium of the sail when it has been disturbed upon a variation in the pressure upon any portion of the surface of the sail.

2. A flying machine having, in combination, a substantially flat aeroplane of substantially rectangular form elongated trans-

versely to the line of flight, propelling means, and automatically operating mechanical means controlled by the propelling means for restoring the equilibrium of the aeroplane when it is disturbed by excess vertical pressure upon any portion of the 70 surface of the aeroplane.

3. A flying machine having, in combination, a plurality of parallelly arranged flat aeroplanes elongated transversely to the line of flight, uprights connecting the edges of 75 said aeroplanes to maintain their equidistance, propelling means, and automatically operating mechanical means controlled by the propelling means for restoring the equilibrium of said aeroplanes when it is disturbed by excess vertical pressure on any portion of the surface of said aeroplane.

4. A flying machine, having, in combination, a motor, a horizontally arranged aeroplane elongated transversely to the line of 85 flight and fulcrumed for angular movement relatively to the motor about a fore and aft axis, and means acting on the aeroplane to restore its lateral balance when disturbed by excess vertical pressure on 90 either side of said axis, substantially as described.

5. A flying machine, having, in combination, a horizontally arranged sail constructed and arranged to support the weight 95 by reactions resulting from a movement of said sail through the air, and means for restoring the equilibrium of the machine, when disturbed, by successive increments of return movement of the sail in one direction 100 until the normal position of the sail and consequent equilibrium of the machine has been regained, substantially as described.

6. A flying machine, having, in combination, a substantially flat aeroplane elongated 105 transversely to the line of flight, and means to restore the equilibrium of the machine, when said equilibrium has been disturbed, by a succession of substantially vertical movements of the aeroplane all in the same 110 direction, substantially as described.

7. A flying machine, having, in combination, a substantially flat aeroplane adapted to move through the air edgewise at a pre-determined angle of incidence and supported for both lateral and fore and aft dipping, means to vary the angle of incidence to control the vertical flight, and mechanical actuating devices for said means normally inoperative and rendered operative 115 by a change in the angular relation of the aeroplane to its normal position, substantially as described.

8. A flying machine, having, in combination, a normally flat aeroplane, a support 125 for said aeroplane permitting lateral dipping thereof, means adapted to impart to the aeroplane a helicoidal warp around a central axis transverse to the line of flight, actuating devices therefor, and operative 130

connections between said means and actuating devices, the operation of said devices being controlled by a dipping of the aeroplane to either side, substantially as described.

9. A flying machine, having, in combination, a substantially flat aeroplane adapted to move edgewise through the air at a predetermined angle of incidence and having 10 stiff spars at its lateral margins, a two part rock shaft extending between said spars having a part rigidly connected centrally to each spar, a frame in which the two parts of said rock shaft are journaled and means 15 for rocking the parts of said shaft in opposite directions to obtain different angles of incidence at the opposite end portions of the aeroplane, substantially as described.

10. A flying machine, having, in combination, 20 a U-shaped frame, an aeroplane, adapted to move through the air edgewise at a predetermined angle of incidence, supported in said frame, said aeroplane being journaled in said frame on transversely arranged pivots to permit a variation of the angle of incidence, and automatic means for controlling the degree of said angle, substantially as described.

11. A flying machine, having, in combination, 30 an aeroplane supporting frame fulcrumed for angular movement about a horizontal fore and aft axis, an aeroplane sustained in said frame fulcrumed for angular movement about a horizontal transverse axis, and automatic means for controlling the movement of said aeroplane about said axes, substantially as described.

12. A flying machine, having, in combination, 40 an aeroplane supporting frame fulcrumed for angular movement about a horizontal fore and aft axis and provided with upright standards centrally of its lateral ends, a pair of aeroplanes sustained in said frame each having end bearings fulcrumed 45 in said standards for angular movement about a horizontal transverse axis, and means connecting said aeroplanes, to maintain their equidistance, constructed and arranged to permit of said angular movements, 50 substantially as described.

13. A flying machine, having, in combination, 55 an aeroplane adapted to move through the air edgewise at a predetermined angle of incidence and mounted for fore and aft dipping movements whereby said angle may be altered, and means for restoring said angle to its normal value after disturbance of the equilibrium by excess pressure on the front or rear of the aeroplane comprising 60 mechanical means for dipping the aeroplane, a movable centering cam for controlling the action of said means, and a float mechanism for governing the position of the cam according to the degree of the loss of equilibrium, substantially as described.

14. A flying machine, having, in combination, a substantially flat aeroplane adapted to move through the air edgewise and mounted for lateral dipping movements, and means for restoring the lateral balance of 70 said aeroplane after disturbance by excess pressure on either side comprising a movable centering cam, operative connections between said cam and the aeroplane for governing the position of the cam according to 75 the direction and the degree of the loss of lateral balance, and means actuated by said cam constructed and arranged to manipulate the aeroplane in a manner to present its opposite sides to the atmosphere at different 80 angles of incidence, substantially as described.

15. A flying machine, having, in combination, means constructed and arranged to support the weight by the reactions resulting 85 from a movement of said means through the air, and automatically operating mechanical means to restore the equilibrium of the machine when disturbed, said automatically operating mechanical means being constructed 90 and arranged to permit of an adjustment by the operator when desired, substantially as described.

16. A flying machine, having, in combination, 95 means constructed and arranged to support the weight by the reactions resulting from a movement of said means through the air, means under control of the operator to determine the angle of flight to the horizontal while traveling in a vertical plane to 100 bring the machine to the level to be maintained, and automatically operating mechanical means to maintain the equilibrium of the machine while traveling on said angle and level, substantially as described. 105

17. A flying machine, having, in combination, 110 an aeroplane, a vertical rudder, and automatically operating mechanical means for simultaneously moving the opposite lateral end portions of the aeroplane into different angular relations to the normal plane of the body of the aeroplane and to each other, so as to present to the atmosphere different angles of incidence, and for causing the rudder to present to the wind that side thereof nearest the side of the aeroplane having the smaller angle of incidence and offering the least resistance to the atmosphere, substantially as described. 115

18. A flying machine, having, in combination, 120 two aeroplanes, each normally flat and elongated transversely to the line of flight, uprights having flexible joints connecting the edges of said aeroplanes to maintain their equidistance, automatically operating 125 mechanical means for simultaneously imparting to each of said aeroplanes a helicoidal warp around an axis transverse to the line of flight and extending centrally along the bodies of the aeroplanes in the di- 130

rection of their elongation, a vertical rudder, and automatic means whereby said rudder is caused to present to the wind that side nearest the side of the aeroplanes having the 5 smaller angle of incidence and offering the least resistance to the atmosphere, substantially as described.

19. A steering apparatus, having, in combination, a rudder, a compass, automatic means to turn the rudder in a direction to restore the moving object to its course upon a deviation therefrom, and mechanical devices connected with the compass needle for controlling the action of said means, substantially as described.

20. A steering apparatus, having, in combination, a rudder, automatic means for operating the rudder to maintain the moving object on a given course, a compass, and me-

25. chanical devices carried by the compass for controlling the amount of the rudder movement according to the degree of deviation from the course, substantially as described.

21. A steering apparatus, having, in combination, a compass, a course setting device mounted to swing with the compass needle, means for locking said device in any desired angular relation to the needle, a rudder, and mechanical connections between the course 30 setting device and rudder operating to automatically turn the rudder to restore the moving object to its course upon a deviation therefrom, substantially as described.

22. A steering apparatus, having, in combination, a rudder, a compass, a gage device mounted to swing with the compass needle, a feeler arranged to contact with said gage device, and an actuating mechanism for the rudder the action of which depends on the 35 position of the feeler, substantially as described.

23. A steering apparatus, having, in combination, a rudder, a compass, a gage device mounted to swing with the compass needle, a feeler arranged to contact with said gage device, an actuating mechanism for the rudder, a device the position of which determines the action of the actuating mechanism, and means for positioning said device 45 in accordance with the position of the feeler, substantially as described.

24. A steering apparatus, having, in combination, a rudder, a compass, a gage device mounted to swing with the compass needle, a feeler arranged to contact with said gage device, an actuating mechanism for the rudder, a device the position of which determines the action of the actuating mechanism, and means for positioning said device 55 in accordance with the position of the feeler and locking it in position during the action of the actuating means, substantially as described.

25. A steering apparatus, having, in combination, a rudder, a compass, a gage device

mounted to swing with the compass needle, a feeler arranged to contact with said gage device, an actuating mechanism for the rudder the action of which depends on the position of the feeler, and means for locking the 70 compass needle against movement during the engagement of the feeler with the gage device, substantially as described.

26. A steering apparatus, having, in combination, a rudder, a movable centering cam 75 for controlling the angular position of the rudder, a compass, a gage connected with the compass needle, and operative connections between said cam and gage constructed and arranged to impart a movement to 80 the cam proportionate to the degree of deviation of the moving object from its course as indicated by the gage on the compass, substantially as described.

27. A controlling mechanism for control- 85 ling or guiding the direction of movement of a moving object, having, in combination, a feeler arranged to engage the periphery of a relatively moving gage device, and an actuating mechanism the action of which depends upon the position of the feeler, substantially as described.

28. A controlling mechanism for control- 95 ling or guiding the direction of movement of a moving object, having, in combination, a feeler arranged to engage the periphery of a relatively moving gage device, an actuating mechanism the action of which depends upon the position of the feeler, and means for locking the gage device against 100 movement during the engagement of the feeler with the gage device, substantially as described.

29. A controlling mechanism for control- 105 ling or guiding the direction of movement of a moving object, having, in combination, a feeler arranged to engage the periphery of a relatively moving gage device, actuating mechanism, a device the position of which determines the action of the actuating mechanism, and means for positioning said device in accordance with the position 110 of the feeler, substantially as described.

30. A controlling mechanism for control- 115 ling or guiding the direction of movement of a moving object, having, in combination, a feeler arranged to engage the periphery of a relatively moving gage device, actuating mechanism, a device the position of which determines the action of the actuating mechanism, and means for positioning said device in accordance with the position 120 of the feeler and locking it in position during the action of the actuating means, substantially as described.

31. A flying machine having, in combination, an aeroplane arranged to move through the air edgewise and support its weight by the reactions resulting therefrom, said movement of the aeroplane being at 125 130

5 a predetermined angular relation to the horizontal, propelling means, and automatically operating mechanical means controlled by the propelling means for restoring the aeroplane, when disturbed, to its predetermined angular relation to the horizontal.

10 32. A flying machine having, in combination, an aeroplane normally flat and elongated transversely to the line of flight, means co-incident with the transverse axis of said aeroplane, for imparting to it a helicoidal warp about said transverse axis, and means for actuating the warping means, substantially as described.

15 33. A flying machine having, in combination, an aeroplane normally flat and elongated transversely to the line of flight, a two-part rock shaft located co-incidently with the transverse axis of said aeroplane, the parts of which are adapted to be rocked in opposite directions, means operated by the shaft to impart to said aeroplane a helicoidal warp about said transverse axis when said shaft is rocked, and means for 20 rocking said shaft, substantially as described.

30 34. A flying machine having, in combination, an aeroplane adapted to move edgewise through the air and to support the weight by the reactions resulting thereby, said aeroplane being adapted to move at a predetermined angle of incidence and having stiff spars at its lateral margin, a two-part rock shaft extending between said 35 spars having a part rigidly connected centrally with each spar, a frame in which the two parts of said rock shaft are journaled, and means for rocking said shaft in the same direction or in opposite directions, 40 substantially as described.

45 35. A flying machine having, in combination, an aeroplane adapted to move through the air edgewise at a predetermined angle of incidence and mounted for fore and aft dipping movements whereby said angle may be altered, and means for restoring said angle to its normal value after disturbance of the equilibrium by excess pressure on the front or rear of the aeroplane, comprising 50 mechanical means for dipping the aeroplane, and a float mechanism for governing the equilibrating action of said mechanical means, substantially as described.

55 36. A flying machine having, in combination, a substantially flat aeroplane adapted to move through the air edgewise and mounted for lateral dipping movements, and means for restoring the lateral balance of said aeroplane after disturbance by excess pressure on either side comprising a 60 centering cam and operative connections between said cam and the aeroplane, substantially as described.

65 37. A flying machine having, in combination, a substantially flat aeroplane adapt-

ed to move through the air edgewise in a given course, and means for restoring said aeroplane to its balance and course after disturbance by excess pressure on any part thereof comprising a centering cam and operative connections between said cam and the aeroplane, substantially as described.

70 38. A flying machine having, in combination, a substantially flat aeroplane having its opposite lateral end portions capable of movement to different positions below or above the normal plane of the body of the aeroplane, said movement being about an axis transverse to the line of flight whereby said lateral end portions may be moved to 75 different angles relatively to the normal plane of the body of the aeroplane so as to present to the atmosphere different angles of incidence, and automatically operating mechanical means for so moving said lateral end portions, substantially as described.

80 39. A flying machine having, in combination, an aeroplane normally flat and elongated transversely to the line of flight, and automatically operating mechanical means 85 for imparting to said aeroplane a helicoidal warp about an axis transverse to the line of flight and extending centrally along the body of the aeroplane in the direction of its elongation, substantially as described.

90 40. A steering apparatus having, in combination, means for setting a moving object in a given course, a guiding device, and automatically operating mechanical means for turning said device in a direction to 95 restore the moving object to the given course upon deviation therefrom, substantially as described.

100 41. A flying machine having, in combination, an aeroplane adapted to move through the air edgewise and sustain the weight by the reactions resulting therefrom, and automatic means for restoring the machine when disturbed, to a state of equilibrium by causing the aeroplane to 105 move in one direction only until the equilibrium of the machine has been regained, when said restoring movement ceases.

110 42. A steering apparatus having, in combination, means for setting a moving object 115 in a given course, a guiding device, and automatically operating means for turning said device in a direction to restore the moving object to the given course upon deviation therefrom, the movement imparted to the device being proportionate to the amount of deviation of the object from its given course, substantially as described.

120 43. A steering apparatus having, in combination, means for setting a moving object 125 in a given course, a rudder, a compass, automatic means to turn the rudder in a direction to restore the object to its course upon deviation therefrom, and devices connected with the compass needle for con-

trolling the action of said automatic means, said compass and said object being constructed and arranged to permit the object to deviate any amount from its given course 5 and at the same time permit the compass needle to remain in the lines of magnetic stress, substantially as described.

In testimony whereof I affix my signature, in presence of two witnesses.

ERASTUS E. WINKLEY.
